UNITED STATES PATENT OFFICE.

GEORG FORNER, OF BERLIN, GERMANY, ASSIGNOR TO GENERAL ELECTRIC COMPANY,
A CORPORATION OF NEW YORK.

REGULATING DEVICE FOR TAPPED TURBINES.

1,076,413.

Specification of Letters Patent. Patented Oct. 21, 1913.

Application filed March 21, 1912. Serial No. 685,233.

To all whom it may concern:

Be it known that I, GEORG FORNER, a subject of the King of Prussia, residing at Berlin, Germany, have invented certain new and useful Improvements in Regulating Devices for Tapped Turbines, of which the following is a specification.

This invention relates to elastic-fluid turbines or engines from which a supply of steam at relatively low pressure is taken for heating or other industrial purposes after the steam has had its pressure reduced by doing work in the preceding portion of the turbine by driving the load. In many such cases it is necessary that the pressure of the steam at the place of its consumption for heating or the like be kept approximately uniform. The present invention aims to accomplish this by the provision of means whereby the withdrawal of steam from an intermediate or other point of the turbine is caused to occur from a stage or region of higher or lower pressure, depending upon the steam pressure prevailing in a given portion of the turbine. The pipe through which the industrial steam is withdrawn is controlled by a suitable valve, adapted to place such pipe in communication with one or another of several stages of the turbine or with the live steam supply to the initial stage or region of the turbine. This valve is automatically shifted from one position to another to alter the supply of steam so as to maintain the pressure in the industrial system. The automatic shifting of the valve is effected by a movable abutment exposed to the steam pressure in one of the stages or regions of the turbine, so that said abutment will respond to pressure changes in said stage and will therefore shift the valve as said pressure varies.

The accompanying drawing is a diagrammatic representation of a multistage turbine shown in longitudinal section and equipped with my invention.

The turbine has the usual casing 1, shaft 2, bucket wheels 3 mounted on said shaft between the stationary diaphragms 4, and the live steam supply main 5 controlled by a valve 6 which is governed by a speed-responsive device 7. Steam for industrial purposes is withdrawn through the pipe 8 which communicates with a chest 9 in which a slide valve is located. Said valve is preferably of the piston type, as shown at 10,

and contains a transverse passage 11 adapted to register with a plurality of ports 12, 13 and 14 which communicate respectively with three stages of the turbine. Each port is provided with a check valve 15 which closes toward the stage from which said port opens. An additional port 16 is connected by a pipe 17 directly with the live steam main 5. The number of ports may be varied to suit the conditions of any given system, but if their number is small, it may be found desirable to introduce into the heating pipe a pressure-reducing valve 18, to maintain the heating pressure as nearly constant as possible in spite of considerable variations between the pressures derived from the adjacent ports.

The slide valve 10 is operatively connected with a movable abutment exposed to the steam pressure in one of the stages of the turbine. Such abutment is preferably a piston 19 working in a cylinder 20 which communicates at one end with the stage of the turbine selected; for example the stage 21. The pressure of the steam on one side of this piston is opposed by a spring 22 abutting against its other side, and provided with suitable means 23 for adjusting its tension if desired. The piston rod 24 is pivotally connected to one end of a lever 25 fulcrumed at 26 and having its other end pivotally connected with the slide valve 10.

The operation of the device is as follows: If, for example, in consequence of increased consumption of heating steam, the pressure at the tap point falls, then of course the pressure will fall also in the stage 21. The spring 22 is therefore enabled to move the piston 19, and this motion is communicated by the lever 25 to the slide valve 10, so that the passage 11 is brought into line with the port opening from the stage of next higher pressure. This produces a restoration of the pressure of the steam in the heating system to its normal value. Inasmuch as the movement of the slide valve takes place gradually, the opening of the port of higher pressure is also gradually effected, so that great variations of pressure in the heating system are avoided. Moreover, as the slide valve moves, the passage 11 may at some time be in communication with two ports simultaneously. This would permit the higher pressure steam to flow from the stage of higher pressure directly

to the next lower one, were it not for the check valve 15 which closes the port through which the steam attempts to find its way into the lower stage. In case the demand for heating steam is greater than the turbine can supply, the valve 10 will move so far to the left as to put the port 16 in communication with the heating pipe, whereby live steam from the main 5 will be fed directly to the heating system.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

20 What I claim as new and desire to secure by Letters Patent of the United States, is—

1. The combination with a turbine provided with a pipe for supplying steam for industrial purposes, of means regulating the flow of steam to such pipe and controlled by the steam pressure prevailing in a given stage of said turbine.

2. The combination with a turbine provided with a pipe for supplying steam for industrial purposes, of means for regulating the flow of steam to such pipe, and a movable abutment controlling said means and responsive to variations of pressure in a given stage of said turbine.

35 3. The combination with a turbine provided with a pipe for supplying steam for industrial purposes, of means for regulating the flow of steam to such pipe, a piston exposed to the steam pressure in a given stage of said turbine, and operative connections between said piston and the said regulating means.

4. The combination with a turbine having

a plurality of ports opening from several stages, a heating pipe, a valve for putting said pipe into communication with one or another of said ports, and a movable spring-actuated abutment exposed on one side to the pressure of the steam in a given stage of said turbine, and operatively connected with said valve.

5. The combination with an engine having a plurality of ports communicating with stages or regions of different pressure in said engine, of a conduit for supplying steam for industrial uses, valve means for regulating the flow of steam between the ports and the conduit, and a device responsive to the pressure in a given stage or region of the engine for controlling the valve means.

6. The combination with an engine having a working passage in which there are regions of different pressures, of a conduit for delivering steam from a given region for industrial purposes, and means responsive to the pressure in another region for controlling the supply of steam to the conduit.

7. The combination with a turbine having stages or regions of different pressures, of a conduit for delivering steam from a given stage or region for industrial uses, means for regulating the flow of steam between said region and the conduit, and a movable abutment for controlling said means that is responsive to the pressure in a region other than the one from which the conduit receives steam.

In witness whereof, I have hereunto set my hand this second day of March, 1912.

GEORG FORNER.
